(57) **CLAIM**

The ornamental design for a ring connector, as shown and described.

DESCRIPTION

FIG. 1 is a perspective view of a ring connector.

FIG. 2 is a front view of the ring connector of FIG. 1.

FIG. 3 is a back view of the ring connector of FIG. 1.

FIG. 4 is top view of the ring connector of FIG. 1.

FIG. 5 is bottom view of the ring connector of FIG. 1.

FIG. 6 is a left side view of the ring connector of FIG. 1.

FIG. 7 is a right-side view of the ring connector of FIG. 1; and,

FIG. 8 is a front view of a ring connector connecting two rings.

Portions of the ring connector shown in broken lines form no part of the claimed design, and the broken lines in FIG. 8 showing rings are for the purpose of illustrating environmental structure and form no part of the claimed design.

1 Claim, 8 Drawing Sheets(56)
